BOW

Filed Oct. 28, 1927

INVENTOR:

Robert H. Cowdery

Frank M. Slough,
his attorney.

UNITED STATES PATENT OFFICE

ROBERT H. COWDERY, OF GENEVA, OHIO, ASSIGNOR TO THE AMERICAN FORK & HOE COMPANY, OF CLEVELAND, OHIO, A CORPORATION OF OHIO

BOW

Application filed October 28, 1927. Serial No. 229,297.

My invention relates to bows and relates to bows adapted for use in the art of archery.

From prehistoric times the bow and arrow has been commonly known and as a weapon was made by prehistoric man from reed, and wood materials and in more recent times, bows have been commonly made of yew, although in oriental countries, bows have been and are still commonly made of bamboo.

Although bows of metallic material have from time to time been proposed for use, the use has not as yet attained any considerable degree of success, since if the properties of resiliency are sufficiently secured the bow will yield, since commonly these bows are of undue weight or the different portions of the bow are improperly proportioned as to flexure and weight; also difficulty has been had from breakage of metallic and other bows.

An object of my invention, therefore, is to provide a bow so constructed as to possess the property of resiliency distributed throughout the different parts of the bow in such a manner as to achieve the best results as to length or flight of the arrow projected from the bow and to secure accuracy of direction of flight.

Another object of my invention is to provide a bow having its resilient portions so formed as to eliminate the danger of breakage of these portions when the bow is drawn, at the same time permitting the flexure of these portions in such a way as to accomplish the desired properties of flight, distance and accuracy to an unusually high degree.

Another object of my invention is to accomplish the production of a bow which may be readily disassembled into two separate parts during periods of non-use.

Another object of my invention is to produce a bow which will not be subject to warping, in which the amount of yield of the various portions can be, during the manufacturing process of such bows in quantities, accurately predetermined, and to provide a bow which is relatively "non-tiring", so that little attention need be given to the unstringing of the bow immediately after each use of the same; and so that the bow will always be ready for use having the same preliminary

form prior to stringing, or expressed in another way, which will exert the same amount of tension upon the cord when strung.

Another object of my invention is to provide a novel method of making bows of steel applicable to the efficient production of bows possessing uniform qualities, in large quantities.

Other objects of my invention and the invention itself will become apparent by reference to the following description of a preferred embodiment of my invention, illustrated in the accompanying drawing, wherein:

Fig. 1 is an elevational view of a strung bow so constructed as to embody the principles of my invention; 65

Fig. 2 is a similar view enlarged of the bottom end portion of the bow of Fig. 1;

Fig. 3 is a view partly in longitudinal medial section of a part of the handle or paradox portion of the bow of the foregoing figures; 70

Fig. 4 is an end view of the paradox as viewed from either end with the limbs of the bow removed therefrom; 75

Figs. 5 to 12, inclusive, are transverse sections taken on the lines 5—5, 6—6, of Fig. 13, and on lines 7—7, 8—8, 9—9, 10—10, 11—11 and 12—12, respectively, as indicated in Fig. 1; 80

Fig. 13 is an enlarged view of one of the limbs of the bow with an intermediate fragment thereof omitted so as to permit the view to be had on the sheet of drawing of limited size; in the view of Fig. 13 there is indicated in lines of section 5—5 and 6—6 of Figs. 5 and 6; 85

Fig. 14 is a section taken on the line 14—14 of Fig. 3; 90

Fig. 15 illustrates an isometric view, a fragment of the bow limbs receiving the sleeve shown at 3 in Fig. 3, telescoped within the paradox which receives the oppositely extending limbs of the bow; and 95

Fig. 16 is an isometric view of the tube forming the supporting body of the paradox.

Referring now to the different figures of drawing, in all of which where like reference characters occur they refer to the same parts, 100

at 1 and 2, I show a pair of like limbs for a bow, each preferably of highly tempered steel and each alike being gradually tapered in transverse cross-sections from their shank portions shown for the limb 2 at 4, Fig. 13, to their tips, the tip for the limb 2 being shown at 5, each of the limbs terminate at their tips in bow-string supporting hooks 6.

At 7, I show a bow paradox tubular body comprising a metallic tube, supporting at an intermediate portion, a handle sleeve 8, and at its end caps 9; on its interior the tube 7 supports a tubular sleeve 15 telescoped within it and formed substantially alike in all transverse sections, as indicated in Fig. 14 of substantially hollow T-shape. The sleeve 15 is wedged tightly in place in telescoped position within the tube 7 by a pair of strips 18 and 19 of wood or other material adaptable for the purpose of being tightly driven between the inner walls of the tube 7 and the opposing walls 20-21 and 22-23 of the tubular sleeve. Each of the wood strips 18 and 19 are so formed in transverse sections that when driven into the spaces as indicated in Fig. 14, between the tubular sleeve 15 and the inner walls of the tube 7, the sleeve 15 will be tightly wedged in place within the tube 7 and in its wall 24 which is substantially of the form of a segment of a cylinder pressed tightly into intimate engagement with the inner walls of the tube.

I preferably make the sleeve 15 from a cylindrical tube by pinching and pressing inwardly lateral portions of one side of the tube to form the portion which is substantially V-shaped in cross-section, shown at 25, leaving the wall 24 to partake of its original cylindrical form and the radius of curvature 40 I preferably make slightly less than the radius of curvature of the inner walls of the tube 7, so as to permit a slight yielding of the wall 24 when the wood wedging strips 18 and 19 are driven home, whereby intimate engagement of the engaging cylindrical walls of the telescoped tubes will be had, as illustrated in Fig. 14. Having tightly wedged the bow and receiving tube 15 of substantially hollow T-shaped section, as illustrated in Figs. 14 and 15, into the paradox tubular body 7, I then tightly press the end caps 9 over the ends of the tube 7. The caps 9 each contain a slot approximately T-shaped as indicated in Fig. 4 at 10. These slots 55 are so formed as to be capable of alignment with the passage of similar cross-sectional forms provided through the tubular sleeve 15 whereby the properly formed shanks 4 of the bow ends may be projected through the aligned slots 10 in the caps and into the interior of the tubular sleeve 15, as shown at 29.

I refer to the limbs 1 and 2 herein as being of approximately T-shaped sectional form, tapered from shank to tip and prefer-

ably with a reversely tapered shank, but preferably these limbs comprise an arcuate belly 11 having a conversely rounded outer surface and a concave back provided with a rib 12 extending rearwardly along the back from its longitudinal middle concave surface. This formation of bow limb effects the production of a metallic spring giving exceedingly good results used as a bow limb. The provision of arcuate back and an integral longitudinal rib extending medially along its concave side accomplishes a reinforced spring construction receiving slight flexing efforts and wherein the yield in the various portions is very readily predetermined by variations in the dimensions of the rib and the width of the arcuate belly as substantially illustrated in Figs. 5 to 12, inclusive. The reinforcing rib 12 decreases in the amount of its projection from the concave surface of the bow limb towards the tip and adjacent the tip, as illustrated in Figs. 9, 10 and 11, is so reduced as to permit greater flexure of these tip portions and terminates in the nocks or hooks 6 suitably formed as shown to receive the end loops 13 of the bow string 14.

A hand grip is provided in the form of an annular sleeve 26 telescoped over the tubular paradox body 7 and kept in place in the position best indicated in Fig. 1 by flanged collars 27 and 28 which are soldered or otherwise secured in place on the exterior of the tube 7 in compressive contact with the grip.

The shanks 4 of the two bow limbs extend into opposite ends of the paradox through the slots 10 and into opposite ends of the tubular sleeve 15, and in order to accomplish a very tight fit of the limbs within the paradox, I preferably make the shank portions 4 tapered in cross-sectional shape in all transverse directions, and the relative transverse dimensions of the limb shanks and the passage way within the sleeve 15 are made so that a gradually tighter and tighter fit is had by the shanks within the tubular sleeve and whereby the shanks when forced to their in-most positions within the sleeve will be very tightly gripped by the slightly resilient metallic walls of the sleeve, compressed inwardly by the wedging wood packing strips 18 and 19.

I find that it is often desirable to form the limbs of the bow in portions approaching the tip with the belly made gradually more and more of flattened form so as to gradually increase the flexibility of the tip portions to secure the beneficial effect of flexure of tips.

Although both of the bow limbs may be made capable of removal, I sometimes prefer to so tightly wedge one of the limbs, for instance the limb 2, within the tubular sleeve 15, that any ordinary pull will not remove this limb of the bow from the paradox or

handle. This may be done in a number of ways, but a ready way to accomplish this is to interpose a thin sheet of packing material intermediate the shank 4 of the limb 2 and the inner walls of the sleeve 15, so as to make a much tighter engagement, as is the case between the limb 1 and the sleeve 15.

A bow constructed as described I find can be made in quantities of uniformly good quality and without any reasonable liability of its being broken in use. The outer metallic surfaces of the bow comprising surfaces of the limbs and the tubular paradox may be suitably coated or oxidized so as to prevent rusting of the limbs.

Having thus described my invention I am aware that numerous and extensive departures may be made from the invention herein illustrated and described but without departing from the spirit of my invention.

I claim:

1. A bow for archery comprising a pair of oppositely-extended bow limbs and an intermediately disposed handle joining the shanks of said limbs, said limbs each provided with an integrally formed reenforcing rib on its back side, extending longitudinally thereof, said rib being progressively tapered from the handle towards the tip of the limb.

2. A bow for archery comprising a pair of oppositely-extended bow limbs and an intermediately disposed handle joining the shanks of said limbs, said limbs being of substantially T-form in approximately all transverse sections, the stem portion of said sections constituting a longitudinal extending reinforcing rib for the back of the limb, the divergently extending arm portions of said sections together making a substantially U-shaped belly for the bow limb, from the intermediate concave face of which the rib extends.

3. A bow for archery comprising a pair of oppositely-extended bow limbs and an intermediately disposed handle joining the shanks of said limbs, said limbs each provided with an integrally formed reenforcing rib on its back side, extending longitudinally thereof, said rib being progressively tapered from the handle towards the tip of the limb, and a bow-string supporting horn integrally formed with said rib, projected there longitudinally from the tip end thereof.

In testimony whereof I hereunto affix my signature this 14 day of October, 1927.

ROBERT H. COWDERY.
